SINEW EXTRACTING DEVICE

Filed Sept. 18, 1940

UNITED STATES PATENT OFFICE

2,281,442

SINEW EXTRACTING DEVICE

Louis Jacob, New York, N. Y., assignor to
Fred Jacob, Bronx, N. Y.

Application September 18, 1940, Serial No. 357,275

4 Claims. (Cl. 17—11.3)

This invention relates to new and useful improvements in sinew extracting devices, and relates more particularly to a device of this character having improved means for supporting the leg of a turkey, chicken or other fowl while the sinews or tendons are being extracted or withdrawn from the edible portion of the leg.

Devices of this general type have been in use, but to a large extent they have been unsatisfactory for the reason that they have been of such dimensions, in order to secure proper leverage, as to consume a large area in which to be operated. It is accordingly one of the principal objects of the present invention to provide a device for withdrawing the tendons from the leg of a turkey or other fowl which will occupy a minimum of space, both when in operation and when the device is not in use.

A further object of the invention is the provision of improved means for firmly securing the lower or bony portion of the leg while the sinews are being extracted. Yet another object of the invention is the provision of an improved device of this character having means for firmly supporting the legs of fowl of different sizes. Still another object is to provide an improved type of supporting means for sinew extractors.

In the drawing:

Fig. 1 is a broken perspective view of the preferred embodiment of the present invention.

Fig. 2 is a side elevation thereof, the view showing a special adaptor in operative position, such adaptor being used to receive and firmly support a relatively small leg while the sinews are being extracted therefrom.

Fig. 3 is a broken top elevation thereof.

Fig. 4 is a side elevation of a modified form of the invention.

Fig. 5 is a perspective view of the adaptor shown in Figs. 2 and 3.

Fig. 6 is a front elevation of the preferred form of clamping means for rigidly securing the device in operative position.

The preferred embodiment of the present invention comprises a base plate 10 formed with a vertical portion 11 at right angles thereto, the upper end of such portion 11 forming a fixed jaw 12 which is closed at its forward end 13 and open at its rear end as shown at 14. Thus there are formed substantially parallel, horizontal jaw portions 15 and 16, the upper portion 15 being provided with a downwardly extending portion 17 adjacent to its rear end.

Adjacent to the lower end of vertical portion 11 there is provided a horizontal aperture which 55

receives a bolt or machine screw 20 which passes through a suitable aperture (not shown) at the inner end of an elongated lever 21, such lever being of sufficient length to provide adequate leverage during the process of extracting the tendon. Formed integrally with the lever 21 adjacent to its inner end is a jaw 23 having spaced, fixed jaw portions 24.

In most butcher shops a substantially square rail 26 is suitably mounted in spaced relation to a wall (not shown) by any suitable means, such rail normally supporting a plurality of spaced hooks or other similar devices. The base plate 10 is rigidly mounted on such rail 26 by means of a substantially U-shaped support 27 which encloses the rail except on its front side, and the rear of base plate 10 is in contact with such front surface. The U-shaped support is further provided with enlarged front terminal portions 30, and screws 31 pass through suitable apertures (not shown) in the base plate 10 and thus firmly secure the plate and its integrally formed jaw portion 12 to the rail 26.

In use, the lower portion of the leg of the turkey or other fowl is inserted within fixed jaw 12 and bent downwardly until the same breaks and hangs downwardly. This downwardly extending portion is then inserted between the fixed jaw portions 24, and lever 21 moved downwardly, thus severing the tendons from their inner terminals.

In Fig. 2 the base plate 10 is shown as being rigidly secured to a horizontal rail 34 which is generally rectangular in transverse section, rails of this relative size and dimensions being usually formed of steel rather than wood, as shown in Fig. 1. In this instance the U-shaped supporting bracket 35 is formed with shorter horizontal portions, and base plate 10 is secured thereto by means of screws 31.

The adaptor 37 illustrated in detail in Fig. 5 is shown in Figs. 2 and 3 in place on the fixed jaw 12 to reduce the effective width of the jaw portions 15 and 16. This adaptor is desirably cast in a single piece, and includes a lower U-shaped portion comprising walls 38 and 39 which fit over the upper end of vertical portion 11. Formed integrally with wall 38 is an upper offset extension 41 which terminates at its rear end in a horizontal portion 42 having a downwardly projecting vertical portion 43.

A horizontal opening 45 forms spaced jaw portions 46 which are spaced apart a lesser distance than are jaw portions 15 and 16. It will thus be seen that when the adaptor is positioned in the manner shown in Figs. 2 and 3 it is rigid relative

to portion 11, and the jaw portions 46 may receive the lower leg portion of a chicken or other smaller fowl.

A modified form of the invention illustrated in Fig. 4 includes a base plate 51 having a vertical portion 52 terminating at its forward end in an upwardly extending portion 50. Extending rearwardly from said portion 50 are two spaced projections 54 and 53, respectively, providing fixed jaw portions 56 and 57, respectively, the latter set of jaw portions being spaced somewhat further apart than the former. On the lower edges of the terminals of jaw projections 53 and 54 are formed downwardly extending portions 59 and 60, respectively, which act to secure the leg within either of the jaws during the tendon extracting operation.

It will be apparent that other changes and modifications may be made in the foregoing device without departing from the spirit of the invention as defined by the appended claims. In other words, the forms of the invention described herein are illustrative only and are not to be taken in any limiting sense.

What I claim is:

1. In a sinew extractor, the combination of a base plate, a vertical plate formed integrally with and at substantially right angles to said base plate and an inwardly turned projection formed integrally with the upper edge of said vertical plate forming a fixed jaw which receives the leg of a fowl, a downwardly disposed extension formed at the free end of said projection for preventing casual removal of the leg, an elongated lever hinged at its inner end to the lower edge of the vertical plate, and an integrally formed fixed jaw on the lever at a point spaced from the inner end thereof.

2. In a sinew extractor, the combination of a baseplate, means for securing such plate to a horizontal rail mounted in spaced relation to a wall, said means comprising a substantially U-shaped clamping element surrounding the rail and detachable means securing the base plate to the

clamping element, a vertical plate formed integrally with and at substantially right angles to said base plate and an inwardly turned projection formed integrally with the upper edge of said vertical plate forming a fixed jaw which receives the leg of a fowl, a downwardly disposed extension formed at the free end of said projection for preventing removal of the leg during the sinew extracting operation, an elongated lever hinged at its inner end to the lower edge of the vertical plate, and an integrally formed fixed jaw on the lever at a point spaced from the inner end thereof.

3. In a sinew extractor, the combination of a base plate, a vertical plate formed integrally with and at substantially right angles to said base plate and a plurality of spaced inwardly turned projections formed integrally with the upper edge of said vertical plate forming a plurality of fixed jaws of varying widths which receive the leg of a fowl, a downwardly disposed extension formed at the free end of said projection for preventing removal of the leg, an elongated lever hinged at its inner end to the lower edge of the vertical plate, and a fixed jaw formed on the lever at a point spaced from the inner end thereof.

4. In a sinew extractor, the combination of a base plate, a vertical plate secured to said base plate and an inwardly turned projection formed integrally with the upper edge of said vertical plate forming a fixed jaw which receives the leg of a fowl, an adaptor comprising a substantially U-shaped portion positioned on the upper portion of the vertical plate and including an upwardly extending jaw portion of lesser width than the fixed jaw and adapted to reduce the effective width of said jaw, an elongated lever hinged at its inner end to the lower edge of the vertical plate, and an integrally formed fixed jaw on the lever at a point spaced from the inner end thereof.

LOUIS JACOB.
